UNITED STATES PATENT OFFICE

ERIK PATRIK JANSSON, OF EKSJO, SWEDEN, ASSIGNOR TO AKTIEBOLAGET AXEL CHRISTIERNSSON, OF STOCKHOLM, SWEDEN, A COMPANY OF SWEDEN, AND AKTIEBOLAGET EKSJO MEKANISKA VERKSTAD, OF EKSJO, SWEDEN, A COMPANY OF SWEDEN

SAND-SLINGING MACHINE

Application filed May 12, 1928, Serial No. 277,327, and in Sweden May 12, 1927.

The present invention relates to a sand slinging machine for filling sand into moulding boxes and for conveying sand into sand bins and the like. Machines adapted for this purpose are previously known which are provided with a rotary scoop-like member which collects the sand and slings it to the desired place. These old machines operate intermittently, however, since naturally there will be 10 certain time intervals in the feeding of the sand by the scoop.

It has also been proposed to provide an apparatus for the same purpose involving a rotating member having a peripheral groove 15 or pockets into which the sand is introduced externally at one point in the circle of rotation and in which the sand is retained by an endless belt. As a further development of the lastmentioned machine and in order to 20 render it possible to feed the sand to the pockets from an internal point of the rotating member, it has also been proposed to make the rotary slinging member as a hollow rotary body or drum which is provided at one 25 side in the axial direction with a charging or inlet opening for the sand, and with a peripheral groove or slot for slinging out the sand by centrifugal force, said groove or slot being covered along a portion of the periphery of the rotary drum by means of a belt 30 which bears against said periphery and takes part in the motion of the rotary drum, so that during the rotation of the drum the sand is retained within the drum during rotation 35 through that angle which is covered by the belt, until the sand is thrown out at the point where the belt leaves the drum. In said construction the peripheral groove or slot was divided by a series of vanes reaching to the 40 periphery of the drum into a number of pockets, and such machines have therefore also operated more or less intermittently. According to the present invention, however, a continuous and uniform slinging of the sand 45 is obtained.

The present invention is an improvement on the machine last referred to, and consists in that the peripheral groove or slot which communicates with the hollow interior of the 50 rotary drum, is continuous and unbroken

along the entire circumference of the rotary drum. The rotary drum is thus not provided with any vanes dividing the peripheral slot into pockets. The sand will therefore have equal access to all points of the peripheral slot and will be evenly distributed all along the same, so that the stream of sand thrown out at the point where the belt leaves the drum will be continuous as well as uniform and even. 55

An embodiment of the invention is illustrated in the accompanying drawings, in which Figs. 1 and 2 show a sand slinging machine according to the invention, viewed from the side and in vertical axial section, respectively, and Fig. 3 shows a detail of the same. 60

The rotary body or drum is composed of two outwardly convex members or bowls 1 and 2 secured by means of bolts 3 in such manner that a space is formed between said two members 1 and 2 for receiving the sand, and a narrow peripheral opening 4 between the edges of said members. The rotary drum 1-2 is secured to a driving shaft 6 rotatably journaled in the machine frame 5, by means 65 of which shaft the rotary drum is put in rotation. Three belt pulleys 7, 8 and 9 are also rotatably journaled in the frame 5. The pulleys 7 and 8 are secured to shafts 10 and 11, respectively, which are journaled in slides 70 12 and 13, respectively, which may be moved in a direction towards and away from the rotary drum 1-2 by means of hand-wheels 14 and 15, respectively, which bear against the frame 5 and through which screw spindles 16 75 and 17, respectively, pass, which are secured to the slides 12 and 13, respectively. A belt 18 runs over the pulleys 7, 8 and 9 and over a portion of the periphery of the rotary drum 1-2 so that it covers a portion of the opening or slot 4. One member 1 of the rotary drum is provided with a side opening 19 into the lower portion of which a hopper 20 for 80 the sand projects. 85

A rod 21 is provided on each side of the frame 5 and is slidable in a bearing 22 which is pivoted to the frame 5. Each such rod 21 rests on a roller 23 rotatably mounted on the frame 5. 90

Pivoted to the left-hand outer ends of the 100

rods 21, as viewed in Fig. 1, is a plate 24 which is thus movable vertically. Said plate 24 is upwardly convex in cross section and bent downwards in longitudinal section, and is also tapering towards its outer end. The plate 24 may be rotated around its pivot by means of a screw gearing 26 which may be operated by means of a hand-wheel 25. A handle 27 secured to the upper side of the plate 24 serves to raise said plate 24 by swinging the rods 21 and to move said rods longitudinally. The frame 5 is rotatable on a base 29 by the intermediary of balls 28.

The sand is introduced through the hopper 20 in the rotary drum 1-2 and is forced by 15 the centrifugal force against the belt 18 which it follows to the upper point of the rotary drum 1-2 where the belt 18 leaves the drum and thus lays the opening or slot 4 free, so that the sand is slung against the plate 24, as 20 shown in Fig. 1. Owing to the tapering and convex shape of the plate 24 the sand is collected to a thin jet which, owing to the bent-down shape of said plate, is directed against 25 the moulding box 30 in which the sand is packed.

By rotating the plate 24 by means of the hand-wheel 25 and by raising or lowering said plate by swinging the rods 21 in the vertical 30 plane, the packing of the sand in the moulding box may be regulated. By longitudinal displacement of the rods 21 and by rotating the frame 5 the sand jet may be directed to every desired point within a large moulding box or to different boxes.

By raising the belt pulley 7 by means of the hand-wheels 14 the sand jet may be directed upwards, so that the machine may be used for slinging the sand up into bins and the like, 40 in which case the rods 21 and the plate 24 are not used. Such raising of the pulley 7 necessitates, of course, a change of the position of one of the other belt pulleys 8 and 9, if it shall not be necessary to change the length of the 45 belt. For this purpose the belt pulley 8 may be moved inwards by turning the hand-wheels 15, to the same extent as the pulley 7 is raised, and vice versa. While in the embodiment illustrated in the drawings two hand-wheels 14, or 15, respectively, are provided for effecting adjustment of each pulley, it is 50 of course possible instead to make such arrangement that said adjustment is effected by means of a single hand-wheel, in which case 55 the two slides 12, or 13, respectively, are rigidly connected by means of a cross piece, to which a screw is secured which passes through the hand wheel.

The invention is otherwise not limited to 60 the embodiment illustrated in the drawing, but may be modified in several respects without departing from the principle of the invention.

I claim:

65 1. In a sand slinging machine, the combi-

nation of a hollow rotary drum having an axially located filling opening and a peripheral slot communicating with the hollow of said drum and which is continuous and unbroken along the entire circumference of said rotary 70 drum, and a belt bearing against the circumference of said drum and covering said slot over a portion of the periphery of said drum.

2. In a sand slinging machine, the combination of a base, a frame rotatably mounted on said base, a hollow drum rotatable in said frame, said drum having an axially located filling opening and a peripheral slot communicating with the hollow of said drum and which is continuous and unbroken along the 75 entire circumference of said rotary drum, and a belt bearing against the circumference of said drum and covering said slot over a portion of the periphery of said drum.

ERIK PATRIK JANSSON.
